CORE BOX DOWEL PIN

Edwin F. Peterson, Kewanee, Ill.

Application November 16, 1949, Serial No. 127,648

2 Claims. (Cl. 22--13)

1

This invention relates to dowel pins for use in foundry work for registry of composite mold sections and more specifically to dowel pins used for the scope and drag sections of core boxes.

Some of the principal objections to the dowel pins now in use are that the pins work loose, and that they tend to deface and damage the core box. After core removal, the box is closed for further sand insertion, but a careless operator may drop or throw the cope on the drag causing the pins to peen or chip one or the other of the core box parts depending on which part carries the pins. Repeated separation and combining of the core box parts will eventually lead to wear at the pin receiving openings even when such work is carried out by skilled and careful operators.

Loosening of the dowel pins usually is brought on by tapping the mold parts in freeing the core. Larger or more intricate cores may require greater force so that by rapping either section of the core box, the cope or the drag, this force is directly transmitted through the pins. The dowel pins may work loose in the threads, actual play may develop, and these pins may also become bent. Bending of the protruding pins may happen through accident or carelessness when the mold or core parts are left open and particularly with the use of solid metal pins.

The main purpose of the dowel pin of the present invention is to provide a pin that will save the mold or core box parts to considerably prolong the life of such parts and to cut down maintenance costs as well as reducing the costly repair time of such molds or core boxes.

The pin is constructed with a resilient end to prevent damage and wear to the pin receiving core part. And it is a further object of the invention to carry the pin in a resilient mounting whereby the pin will not become bent by accident or through lateral engagement by the core part that is being brought into registry with the pin during normal foundry practice. Dropping of the dowel pin core part will not bend the pins even in the event that the part strikes the floor on a pin, by reason of the resilient or flexible mounting herein disclosed and described.

A still further object of the invention is to provide a dowel pin having the ability to remain tight in the mold or core part to which it connects thus eliminating objectionable loosening of the pins. The pins remain as secured and need no tightening or checking to see if they are still in the position necessary to carry out the foundry work for which they were intended.

By producing a pin with a threaded rubber

2

base a friction element is devised which, when threaded into position in a core box part, resists loosening of the pin structure under normal conditions of use. Any rapping shocks against the box will be absorbed in the body of the rubber mounting to make the latter vibration free. And twofold, the pin will be separated from metal contact with the box to cushion mount the pin in operative position with respect to the box, and in a resilient base counteracting bending of the pin as well as introducing some endwise resiliency to the pin.

The endwise resiliency of the pin will be limited but effective and one of the main objects of this invention is to obtain a pin and rubber base unit with good union to prevent separation of the parts. The use of a hollow pin provides a good bond with a rubber base that not only engages the outside of the pin but extends upwardly through the pin. To carry this idea further, a solid pin can be used with a threaded exterior or other contour for obtaining a good bond with the base rubber molded thereon. Or a sleeve pin with radial openings may be employed to obtain a good bonded union and to place some of the rubber in shear as well as in bonded surface contact.

The dowel pins may be threaded into place in a core box by proper clamping tools to grip the metal pin. Another method is to provide each pin with a special socket in the metal portion for a wrench to fit the socket, the latter being axially located on the pin to increase the ease of attaching or removing a pin.

One other object of the present invention is to construct the dowel pin units in a relative size ratio wherein the pin body is smaller than the body of the base and definitely small enough to be able to pass freely through the core box opening for the dowel pin. This feature is exceedingly important with pins utilized in connection with large long draw boxes that have their respective parts manipulation by power machines.

Any misalignment of the composite core box parts is disastrous to boxes of this type causing bending of the pins and damage or destruction to a costly core making apparatus. With the pin of the present invention, such accidents through carelessness or other conditions are avoided since the pin, if struck by a closing machine actuated part, will shear through the rubber mounting and through the dowel pin hole without bending and causing damage to the core box parts.

Other objects and advantages relating to

dowel pins of this character and invention shall hereinafter appear in the following detailed description having reference to the accompanying drawings forming a part of this specification.

In the drawings:

Fig. 1 is a vertical cross sectional view taken through a conventional core box with the cope and drag registered and in place as determined by the dowel pins of the present invention to illustrate one typical installation of pins of this design;

Fig. 2 is a side elevational view of a dowel pin as the same appears per se, and removed from the core box;

Fig. 3 is an axial cross sectional view of the dowel pin as taken substantially along the line 3—3 in Fig. 2;

Fig. 4 is an end elevational view of the dowel pin as seen from the top in Fig. 2;

Fig. 5 is a transverse cross sectional view through the dowel pin structure taken substantially in the plane of the line 5—5 in Fig. 3;

Fig. 6 is an axial cross sectional view of a modified construction of dowel pin embodying certain other features of advantageous function;

Fig. 7 is a side elevational view of a solid metal pin in a rubber mounting base for use with core making boxes of the long draw type that are adapted to machine operation under power opening and closing of the core boxes;

Fig. 8 is an axial sectional view of a dowel pin of a modified construction;

Fig. 9 is a bottom end view of the pin shown in Fig. 8;

Figs. 10 and 11 are axial sectional views of dowel pins embodying certain other features all contributing to the feasible use and long life operation of dowel pins of this invention;

Fig. 12 is a transverse cross sectional view of the pin in Fig. 11 and as seen substantially along the plane of line 12—12 therein; and

Fig. 13 is a fragmentary view of a core box part in section to illustrate the manner in which a socketed dowel pin may be threaded home in a receiving threaded box opening provided for such a pin.

In Fig. 1, a typical mold or core box 1 is shown having a cope 2, a drag 3 and a plurality of suitably positioned dowel pins such as 4 providing the registering agencies for the cope and drag, and forming the principal devices of this invention. Each of the dowel pins 4 has an externally threaded base 5 with a contiguous flared head 6, and a pin 7 projecting upwardly concentrically with respect to the base and flared head.

Although the dowel pins 4 may be interchangeably used between cope and drag, Fig. 1 shows the dowel pins 4 as secured to the drag 3 with the pins in holes 8 in the cope 2. A receptive sleeve socket 9 for a dowel pin 4 may be used in alignment with the opening 8. Such a sleeve socket 9 may be provided by first drilling a suitable bore, then flaring the bore as at 10 for the head 11 of the sleeve socket 9 and then by reaming followed by tapping the drilled bore with suitable standard thread tape to form the threaded interior 11a for the threaded portion of the sleeve socket 9.

The drag is prepared for receiving the dowel pins 4 in fixed relation thereto by providing threaded openings 12 for the base 5 which openings terminate in smooth conical bores 12a widening outwardly at the parting line of the

core box drag 3 or similar mold part, as best shown to the right in Fig. 1.

Head 6 of base 5 terminates in a transversely positioned shoulder 13 forming a ledge encircling pin 7 and in plane normal to the axis of the pin. The flared counterbore 12a of the threaded hole 12 is proportioned for size and depth to snugly receive the flared head 6 and preferably should be made to bring the shoulder 13 of the head 6 flush with the parting surface plane 14 of the drag 3 or slightly below this plane. Thus the pin 7 projects upwardly from the surface 14 of the drag 3 and each pin terminates with a rounded cap 15.

The pin 7 is a composite unit comprising metal sleeve 16 which is completely filled with a resilient composition or material such as rubber 17 which forms an integral part of the cap 15, the head 6, and the threaded base 5 which are all made out of the same material and are all contiguously formed in a bonded mass. Nesting of the resilient threaded base 5 and its flared resilient head 6 within the threaded opening 12 and conical flare 12a tends to cause compression 25 of the resilient material 17 against the metal sleeve or pin 16. Sleeve 16 is exposed above the shoulder 13 of head 6, but the lower end 18 of such sleeve is fixedly bonded into the head 6 and base 5 as best shown in Fig. 3. The open 30 ends of the sleeve 16 are each flared radially outwardly at 19 and 20 to eliminate right angle metal corners which have a tendency to produce fault lines to weaken the adjacent rubber leading to cracking and final rupture of the adjacent 35 rubber portions at the right angle locations.

The pin 7 is sturdily supported but it has the ability to actually tilt in its rubber mounting comprising the head 6 and base 5 and as indicated in broken lines at 1a in Fig. 3. This is only possible when the cope 2 is not seated upon the drag 3. When seated the pin 7 is held against tilting in hole 8 in the cope 2, and all relative sliding of the cope 2 with respect to the drag 3 along the parting plane 14 is directly and positively counteracted by the pin 7 and heavy rubber flare of the head 6 at the plane of the shoulder 13. In other words, the only possible force on the pins with the cope and drag in place is a transverse shearing force which is never great enough under normal operating conditions to do any harm to the pins 7.

The resilient cap end 15 of the pin presents a cushion on the pin to eliminate all peening of the removable core box part as well as scratching or defacing the same as such part is placed in position upon the pins, etc. This saves the mold or core box parts as well as safeguarding the operator from injury such as can be caused by manual contact with a pin particularly with one that has become burred or defaced. Since the pin 7 is composed of a sleeve 16 and a bonded rubber core 17 with the normal outcrop 15 shown, such a pin will have the further advantage of always presenting a rubber end if the metal sleeve 16 wears at the top edges under continued use. Rubber presents a greater tenacity to wear than metal particularly under conditions where sand is used, so that the rubber wear will be significantly retarded with respect 70 to the wear of the metal parts of the pin. Thus the cushioning function of the dowel pin end will be maintained for the life of the pin.

The threaded base 5 will frictionally resist loosening of the dowel pin once the latter has been 75 screwed tightly into the threaded hole 12, and

this action supplemented by a compressive wedge action of the flared head 6 in the flared opening 12a will hold the dowel pin unit in fixed operative relation in a mold or core box part under all conditions of operation. Tapping, rapping or excessive jarring will not loosen a pin of this construction which is resiliently mounted and insulated by rubber from the metal body of the core box.

And as stated before, the pin can fulcrum within the mounting to tilt, thereby providing a resilient pin support in a fixed socket to counteract bending of the pin even under extreme conditions of unsatisfactory operative use. The base and all of the contiguous integral rubber parts thereof will at all times return the pin to its normal upright position. The pins are also capable of slight compensation for inaccuracies as in cases where three or four pins are in perfect alignment and one is a few thousandths of an inch off. Automatic adjustment is also possible with resilient pins of this kind where the mold or core box parts may undergo some warpage or shrinkage and expansion.

Another important factor is the ability of the pins to shear through their mountings if something should cause misalignment under pressure closing of the core box parts, or if some foreign object should come between the parts.

The dowel pin 21 shown in Fig. 6 is made with a longer threaded base 22 that may be screwed into an appropriately threaded opening in a core box part. The greater thread length circumferentially introduces greater friction to hold the dowel pin fixedly in place after turning and threading the unit into a socket by means of a pair of pliers or other suitable tool. Base 22 also has a shoulder 23 surrounding the sleeve 24 comprising the pin 25 that is headed with a cushion top 26.

This construction embodies further means for frictionally holding the cope in place upon the drag by providing an annular recess 27 around the sleeve 24 and by filling in the recess with an external rubber sleeve 28 as an integral and contiguous part of the rubber structure of the dowel pin 21. The external diameter of the rubber sleeve 28 is preferably made slightly larger than the pin sleeve diameter so that the cope pin bore will tightly and frictionally receive the rubber sleeve 28 when the cope is fully nested upon the drag. Sleeve 28 may be formed at any point along the exposed portion of the pin 25 depending upon the conditions of operation and the action desired. A further embodiment of this kind is shown in Fig. 10.

Fig. 7 shows a pin that is much like the dowel pin shown and described in Figs. 1 to 5. This pin 29 is a solid metal pin having an enlarged shank 30 bonded into a resilient rubber mounting base 31 threaded at 32 and having a flared head 33. This type of pin is used for heavy deep draw work where a power operated machine brings the cope and drag together. A rubber tip could be used on pin 29, but since machine alignment is here employed, the tip can actually be omitted. If something should happen to throw the pin 29 and its receptive opening in cope out of alignment, the pin would be driven through base 31 as indicated by the dot and dash lines 34 and out of the threaded opening 35 in the drag lug 36.

In the forms previously described, the dowel pins are threaded into position by a suitable wrench adapted for clamping the metal pin. Fig.

8 contemplates using a solid metal pin 37 having a hexagonal socket 38 in the exposed bottom end thereof. This pin has a grooved or threaded end 39 to obtain additional bonding surface to fix the pin 37 into the threaded rubber base 40 and thus to permit threading the entire unit into the threaded opening 41 in core part 42 by the use of a hexagonal socket wrench. Base 40 is shown as having an annular flange 43 in place

of a flared head to contemplate using heads of a different shape and as in this case one that has a more abrupt seating surface to come to a fairly definite stop on the shoulder 44 of a core box recess 45.

Fig. 10 demonstrates the use of a covered pin 46 having a base 47 with a rubber cover 48 of normal pin diameter projecting contiguously from the base 47 and over the stem and end of the pin 46. Pin 46 is made with a rough contour at 49 for better bond with the rubber base 47, and the lower end of pin 46 is exposed to present a wrench socket 50 at its axial center for threading the dowel pin unit into place in a core box. The introduction of the socket in pins of this kind makes it possible to rubber coat the pin for a complete protection along its height and at its end.

One further arrangement of a dowel pin structure is shown in Figs. 11 and 12 wherein radial openings or depressions are employed to enhance bonding the hard pin with its resilient mounting and to place some of the rubber in shear to withstand any relative turning loose or parting of the main pin elements. This dowel pin uses a hollow or sleeve pin 51 that may be of an external contour terminating in a common cylindrical plane of pin diameter or round as shown, having a hexagonal interior 52 to receive a wrench therein for securing of the pin with a core part. Pin sleeve 51 is perforated at 53 and a molded rubber base 54 is secured to the sleeve passing through the openings 53 and filling the hexagonal interior to terminate in a cap 55 at its free upper end. In this structure the hexagonal interior of the pin counteracts rotation of the sleeve pin under force while the base 54 is bonded thereto and to the outer surface of the pin, and portions 56 of the base are rubber slugs offering shearing resistance to further restrain relative rotation between the connected down pin parts.

Fig. 13 illustrates how a wrench 57 with an angle handle 58 can be used in a wrench socket 59 of a dowel pin 60 to screw the base 61 into place in a threaded hole thereby seating the head 62 in a core part 63 for operative use. Pins such as shown in Figs. 8 to 12 may be fastened in this manner to position the same in a core box part for operative use in foundry core making or molding practice.

Changes and modifications in the exact structures shown and described are contemplated in carrying out the principles taught by the fundamental inventive concept herein presented. All deviations in the exact form and combination of elements of the dowel pins shall, however, be governed by the breadth and scope of the language of the appended claims defining the invention.

What I claim is:

1. A dowel pin for registering core box parts comprising a metal sleeve having its terminal ends internally flared radially outwardly at their peripheral portions to provide a symmetrical unit, and a molded rubber body bonded to said sleeve and having one portion thereof filling the sleeve

and protruding from one end thereof to form a resilient cap of sleeve diameter on said one end and blending into the exterior contour of the sleeve adjacent the flared portion of the interior of said one end, said body having another portion thereof protruding from the other end of said sleeve and partially covering the exterior of said sleeve to provide means to secure the sleeve into an opening in one of the core box parts.

2. In a dowel pin for registering coacting core box parts wherein one part has an outwardly flared opening therein terminating internally with a threaded bore and the other part has a pin receiving opening therein, the combination of a hard bodied pin for said core box part opening, and a base connected with said pin to secure the latter to said one core box part, said base being constructed of resilient material and comprising a threaded end portion having a flared head thereon, said threaded portion of said base being adapted to frictionally retain the base

within the internally threaded bore of said one core box part, and said flared head of the base comprising means to snugly nest within the outwardly flared opening in said one core box part and adjacent the threaded bore therein.
